UNITED STATES PATENT OFFICE.

ROBERT H. FULTON, OF CHICAGO, ILLINOIS, ASSIGNOR TO CONSOLIDATED STEEL STRAPPING COMPANY, OF CHICAGO, ILLINOIS, A CORPORATION OF DELAWARE.

SEAL.

Application filed May 5, 1922, Serial No. 558,719. Renewed May 10, 1926.

My invention relates to a seal which consists of a metal strip adapted to have its ends interengaged in such manner that the seal cannot be opened and re-closed without detection. Devices of this character are adapted to be employed for a great variety of sealing purposes, as, for instance, in connection with car doors, other doors, cans, boxes, trunks, shipping cases, bags, etc. One method of using the present type of seal for sealing car doors is illustrated in copending application, Serial No. 605,163, filed by myself and John W. Leslie.

The invention consists in the provision of a metal seal of new and unique construction, which is adapted to be threaded through and turned upon itself in a novel manner, and to have its ends interengaged in such fashion that after the seal has been closed it is practically impossible to open and then re-close it without leaving unmistakable evidence of such tampering.

The construction of my improved seal, as well as the preferred method of applying same are fully set forth in the following detailed description, wherein reference is made to the accompanying drawings, in which—

Figure 1 is a top plan view of my improved seal before its ends have been brought together, and threaded one through the other in the manner presently to be explained;

Figure 2 is a bottom plan view of the same;

Figure 3 is an enlarged fragmentary section taken on the line 3—3 of Figure 1;

Figure 4 is a top plan view of the seal as it appears after the first threading operation;

Figure 5 is a bottom plan view of the seal as it appears after the first threading operation;

Figure 6 is an enlarged top plan view of the seal as it appears after the second threading operation, but before the crimping, or distorting, operation;

Figure 7 is a sectional view which may be regarded as taken on the line 7—7 of Figure 6;

Figure 8 is a top plan view, illustrating the connected ends of the seal as they appear subsequent to the crimping, or distorting, operation;

Figure 9 is a bottom plan view illustrating the connected ends of the seal as they

appear after the crimping, or distorting, operation; and

Figure 10 is a cross-sectional view taken on the line 10—10 of Figure 8.

Throughout the several views, similar reference characters refer to similar parts.

Figures 1, 2 and 3 illustrate my improved seal in the form which it is preferably given before being supplied to the user. The seal as shown in these figures comprises an integral, and preferably ductile, metal strip 11, which at one end is provided with lateral wings 12—12, which have been turned away from the strip proper, and toward each other, to provide a sleeve 70 which is adapted to receive the opposite end of the strip, and to embrace the lateral edges of the latter when the strip ends are brought together and interengaged, in accordance with the method presently to be explained. Two parallel slits 13—13 are formed in the sleeve portion of the strip, and the web 14, which lies between these slits, is raised above the plane of the rest of the strip to permit and facilitate the second of the threading operations presently to be described.

That end of the strip 11, which is to be threaded through the hereinbefore-mentioned sleeve, is conveniently pointed, as indicated at 15, and is preferably painted or otherwise colored differently from the rest of the strip. The painted, or otherwise colored portion of the strip, is indicated at 16. If desired, an identifying number or letter or both may appear upon the painted end of the strip, as indicated at 17.

In using the improved seal of my invention, the strip 11 is passed in the usual manner through the parts which are to be sealed against any unwarranted opening or separation. The pointed end of the strip is then threaded through, and extended a substantial distance beyond, the sleeve portion of the strip, as illustrated in Figures 4 and 5. This is the first threading operation. The pointed end of the strip is now turned back over the sleeve portion of the strip, and is threaded through slits 13—13 and under web 14, as is clearly illustrated in Figures 6 and 7. This is the second threading operation. The seal is now ready for the performance of the final, or distorting, operation. This final, or distorting, operation is preferably, but not necessarily, a

crimping operation performed in accordance with the method of Flora United States Patent No. 1,038,108, dated September 10, 1912, and is accomplished by means 5 of a sealing or crimping tool substantially like the tool shown and described in Flora United States Patent No. 1,038,109, dated September 10, 1912.

In performing the final, or distorting, 10 operation, the jaws of the sealing tool are applied to the lateral edges of the sleeve portion of the seal strip, the sealing tool serving simultaneously to crimp the web 14 and wings 12-12 of one end of the strip 15 edgewise into infolding, interlocking engagement with the two embraced thicknesses of the other end of the strip. The slits 13-13 define the points where the jaws of the crimping tool are to be applied, and 20 in a measure facilitate the crimping operation. Figures 8, 9 and 10 illustrate the seal of my invention as it appears after the performance of the crimping operation just described.

25 The seal of my invention when closed in accordance with the method herein described has a very pleasing characteristic appearance, and when once opened cannot be re-closed without the seal bearing unmistakable evidence of tampering. When viewed from the front or top, as illustrated in Figure 8, the colored portions of the seal strip, which lie on either side of the uncolored or differently colored web 14, are 30 very conspicuous. Any unauthorized attempt to violate the seal by withdrawing the colored end of the strip from under web 14 will so scratch the exposed colored portions of the seal strip as to make it obvious that 35 the seal has been violated. If, in violating the seal, resort should be made to cutting away that portion of the seal strip which properly extends under web 14, violation of the seal would be made evident 40 by a departure from the characteristic appearance of the seal, and by the absence of the identifying markings, numbers or letters, 45 17. Other advantages afforded by the improved seal construction of my invention 50 will be apparent to persons familiar with the art to which my inventions relate.

55 While I have chosen to perform the final step in the application of my improved seal in accordance with and by the method and means described in the Flora patents, hereinbefore mentioned, it is to be understood that my invention contemplates the use of any suitable means for forming the locking deformations in the connected ends of the 60 seal strip.

Having thus illustrated and described my improved seal, and the preferred method of applying same, what I claim as new and desire to secure by Letters Patent of the 65 United States is:

1. A seal comprising a metal strip having one end thereof provided with lateral wings which, together with the adjacent portion of said strip end, provide a sleeve adapted to embrace the other end of the strip, said last-mentioned end of the strip extending through said sleeve and being turned back upon and alongside the sleeve, two thicknesses of said last-mentioned strip end being interengaged with the sleeve by 75 interlocking deformations.

2. A seal comprising a metal strip having one end thereof conformed to provide a sleeve adapted to embrace the other end of the strip, said last-mentioned end of the strip being extended through and beyond said sleeve, and being turned back upon itself and alongside the sleeve, two thicknesses of said last-mentioned strip end being interengaged with the sleeve by interlocking 85 deformations.

3. A seal comprising a metal strip having one end thereof conformed to provide a sleeve, one wall of which has an outwardly offset web, the other end of the strip extending through and beyond the sleeve and being turned back upon the sleeve and passing under said web, two thicknesses of said last-mentioned strip end being interengaged with the sleeve by interlocking 90 deformations.

4. A seal comprising a metal strip provided at one end with lateral wings conformed to embrace the other end of the strip, there being a pair of spaced transverse slits in said first end of the strip, the metal between said slits being pressed outwardly away from the plane of the surrounding metal to provide a web, said second end of the strip extending alongside the first end of the strip, and through and beyond the embrace of said wings, and being turned back upon the first strip end and passing through said slits and under said web, the several contiguous portions of the metal of the strip ends being interengaged by 100 interlocking deformations.

5. A seal comprising a metal strip provided at one end thereof with lateral wings which, together with said strip end, constitute a sleeve, there being a pair of transverse slits in the aforesaid end of the strip, the metal between said slits being offset from the adjacent metal and away from said wings, the other end of the strip passing through the sleeve and thence around the end thereof, and passing through said slits and under said web.

6. A seal comprising a metal strip provided at one end thereof with lateral wings which, together with said strip end, constitute a sleeve, there being a pair of transverse slits in the aforesaid end of the strip, the metal between said slits being offset from the adjacent metal and away from said 125

wings, the other end of the strip passing through the sleeve and thence around the end thereof, and passing through said slits and under said web, the several layers of 5 the metal of the strip ends being conjointly crimped edgewise into interlocking engagement.

7. A seal comprising a metal strip having one end thereof conformed to provide a 10 sleeve adapted to embrace the other end of the strip, said last-mentioned end of the strip being extended through and beyond said sleeve, and being turned back upon itself and alongside the sleeve and outside of 15 portions of the latter, said sleeve comprising an offset web which lies outside of the last-mentioned strip end portion, the ends of the strip being engaged by interlocking deformations.

8. A seal comprising a metal strip having one end thereof conformed to provide a 20 sleeve adapted to embrace the other end of the strip, said last-mentioned end of the strip being extended through and beyond said sleeve, and being turned back upon itself and alongside the sleeve and outside of 25 portions of the latter, said sleeve comprising an offset web which lies outside of the last-mentioned strip end portion, the ends of the strip being engaged by interlocking deformations, and the outer surface of the strip end portion which passes under said web being of different color than the outer surface of said web.

In witness whereof, I hereunto subscribe 35 my name this 2nd day of May, 1922.

ROBERT H. FULTON.
